UNITED STATES PATENT OFFICE.

FRED E. ASELTINE, OF DAYTON, OHIO, ASSIGNOR, BY MESNE ASSIGNMENTS, TO DELCO-REMY CORPORATION, OF DAYTON, OHIO, A CORPORATION OF DELAWARE.

CHARGE FORMING DEVICE FOR INTERNAL-COMBUSTION ENGINES.

Application filed January 26, 1926. Serial No. 83,979.

This invention relates to charge forming devices for internal combustion engines, especially automotive vehicle engines.

This invention provides various improvements and changes over the devices of my prior applications, Serial No. 4,665, filed January 26, 1925 and Serial No. 54,592, filed September 5, 1925.

An important feature of the present invention is the adjustable liquid dash pot for stabilizing and modifying the action of the suction-opened main air inlet valve.

Another feature of this invention is the improved form of primary carburetors, each having a single individual fuel jet, the fuel flow to all of said jets being controlled by a suction actuated gravity valve.

Another feature of this invention is the one-way valve placed in the fuel duct leading to the primary carburetors to prevent back flow of fuel from said carburetors.

Another feature is the depression equalizing duct interconnecting the outlets of the primary carburetors whereby the same engine suction is always applied to each of said primary carburetors.

Another feature is the improved design of air and fuel jets for the primary carburetors for delivering a more uniform rich fuel mixture.

Further objects and advantages of the present invention will be apparent from the following description, reference being had to the accompanying drawings, wherein a preferred form of embodiment of the present invention is clearly shown.

In the drawings:

Fig. 1 is a plan view of a charge forming device for a six cylinder internal combustion engine, built according to this invention.

Fig. 2 is a section on line 2—2 of Fig. 1.

Fig. 3 is a view showing part of the manifold in side elevation but the central portion in vertical section, said section being taken on line 3—3 of Fig. 4.

Fig. 4 is a horizontal section taken on line 4—4 of Fig. 3.

Fig. 5 is a vertical section taken on lines 5—5 of Figs. 4 and 7.

Fig. 6 is a side elevation of the central portion of the device but having parts broken away to show certain interior construction.

Fig. 7 is a plan view of the distributing block, showing the equalizing duct interconnecting the outlets of the primary carburetors in dotted lines.

Fig. 8 is a section on line 8—8 of Fig. 7.

Similar reference characters refer to similar parts throughout the several views.

Numeral 10 designates in its entirety the air manifold provided with the three branches 11, 12 and 13, each of which branches connects to an engine intake port which serves the two adjacent cylinders. Fig. 2 shows only one engine intake valve 15 of the pair of similar valves served by the branched intake passage 14 and intake port 16 in the cylinder block casting.

The air manifold 10 has a main air inlet 70 elbow 17 bolted thereto by bolts 18. The conical main air valve 20 seats upon the lower end of elbow 17. A casting 21 of a general circular form is bolted by bolts 23 to the under side of manifold casting 10 (see Fig. 3). Fixedly mounted in casting 21 is the casting 22 which serves as a vertical guide for the air valve stem 24 and for the dash pot cylinder 25. The dash pot piston 26 is pinned to the lower end of valve stem 24 by pin 27 (see Fig. 5) in such a manner that there is a slight universal movement of the piston 26 on the stem 24. This permits the conical air valve 20 to be self-centering to a certain extent since the guide bearing in casting 22 is made sufficiently loose to permit this. The air valve 20 is held urged to its seat by the coil spring 28 whose upper end seats upon the seat cup 29 suitably attached to stem 24, and whose lower end seats upon the seat cup 30 which is vertically slideable within the cylindrical portion 31 of casting 22. This seat cup 30 may be raised or lowered by a manually operated bifurcated lever 32 which is provided with diametrically opposed lugs 33, each of which rides within a slot 34 in the seat cup 30 (see Figs. 4, 5 and 6). The stationary cylindrical portion 31 is provided with slots 34 of sufficient width to permit the arcuate movement of the lugs 33 extending therethrough. The short shaft 36 upon which lever 32 is mounted has a bearing in the casting 21 and its projecting end has a lever arm 37 which is connected through suitable actuating linkage (not shown) to a control located adjacent the driver's seat. It is thus seen that the driver may manually adjust

the tension of spring 28 at will and thus vary the force which urges the air valve 20 to closed position.

As the air valve 20 is opened by the depression in the manifold 10 the dash pot piston 26 moves down in the cylinder 25 and so damps the opening movement and prevents fluttering of said air valve. Piston 26 has one or more small holes 40 therein which are closed by the 10 disk check valve 41 upon downward movement of the piston but which open upon upward movement thereof. Hence air valve 20 opens slowly according to the leakage past piston 26 but closes relatively quickly due to the 15 opening of check valve 41.

Dash pot cylinder 25 has a by-pass 42 in the wall thereof (see Fig. 3), the upper port 43 of which being located a short distance below the upper edge of piston 26 when air valve 20 is on its seat. Upon downward movement of piston 26 the liquid fuel in the dash pot cylinder leaks past piston 26 around its entire periphery but chiefly passes through by-pass 42 and leaks past the shorter length of the piston 25 between port 43 and the upper edge thereof. As the piston travels down this leakage through by-pass 42 progressively increases until the top edge of piston 26 clears port 43 whereupon there is a sudden decrease in the 30 force resisting the opening movement of air valve 20. The distance between the top edge of piston 26 and port 43 of by-pass 42 when valve 20 is upon its seat may be adjusted to suit requirements by raising or lowering the dash 35 pot cylinder 25, as follows: The lower end of cylinder 25 is rigidly attached to an offset vertical rod 50 whose upper threaded end 51 extends through a hole in casting 21. A gear nut 52 is suitably housed in a recess in casting 21 (see Fig. 3) and is threaded upon the threaded end 51 of rod 50. This gear nut 52 is rotated by the spiral gear 53 on the horizontal shaft 54 which projects laterally outward from casting 21 and has a knurled knob 45 55 thereon. It will now be clear that by rotating knob 55 the gear nut 52 may be turned in either direction and hence the cylinder 25 will be raised or lowered as desired. Preferably a light coil compression spring 56 is provided having its lower end engaging a collar 57 on rod 50 whereby the cylinder 25 is held urged downward at all times, thus avoiding 50 any looseness.

Liquid fuel is maintained at a constant 55 level in the float bowl 60. Fuel enters at the pipe connection 61 and passes down through the valve 62 which is actuated by the float 63 in the well known manner to maintain a constant fuel level. Liquid fuel has free access 60 to the dash pot cylinder above the piston 26 through the slots 35 and thus the dash pot cylinder remains filled at all times.

The primary carbureting devices will now 65 be described. The manifold casting 10 is provided adjacent its central branch 12 with

an integral projection 70. This projection 70 has a vertical duct 71 therein located vertically above the float bowl 60. An extension duct 72 interconnects with projection 70 and extends the duct 71 down below the fuel level 70 in bowl 60 (see Fig. 5). The projection 70 is provided with a flat upper surface or table 73 upon which the distributing block 74 is fixed by means of two screws 75. This block 74 has three parallel drilled passages 76, 77 and 78 therein which constitute the fuel and air mixing passages of the three primary carburetors. The lower surface of block 74 has a liquid fuel distributing canal 80 therein, which canal registers with the vertical duct 80 71 leading fuel up from the float bowl. A removable fuel metering jet 81 leads fuel from canal 80 into each of the passages 76, 77 and 78. An air inlet bushing 82 admits air to each of passages 76, 77, 78 adjacent the fuel jets 81. The inner end of bushing 82 has a projection 83 of slightly reduced diameter which projects above the fuel jet 81 as clearly shown in Fig. 8. The upper part of the projection 83 is cut away on a bias as shown. It has been 90 found that this arrangement of air and fuel jets provides a very uniform fuel mixture even though the proportion of fuel to air is large compared to that delivered by ordinary carburetors. This overrich fuel mixture supplied by the primary carburetors 76, 77, 78 is led individually to the three branches 11, 12, 13 of the air manifold 10.

The branch 13 has a large venturi 90 held therein by the tapered set screw 91 (see Fig. 2). Venturi 90 has a hole 92 on its upper side adjacent the restricted throat which registers with the hole 93 in the branch 13. A rich mixture duct 94 conveys the fuel mixture from the primary carburetor 78 to the hole 93 in 105 branch 13. Air entering the venturi 90 from the main air inlet valve 20 mixes with overrich fuel mixture delivered through hole 92 to form a proper fuel mixture for the engine. The branches 11 and 12 are also provided 110 with venturis 90 similar to branch 13, branch 11 being supplied by primary carburetor 76 through a rich mixture duct 94, while the central branch 12 is supplied directly by the passage 77 in the distributor block 74 (see Fig. 115 8). The manual throttles 95 in each branch have individual throttle shafts 96 which are interconnected by suitable universal joints 97 which permit expansion of the throttle shafts and render exact alignment of all three shafts 120 unnecessary. All three throttles 95 are actuated by the lever arm 98 fixed to the central shaft 96. Arm 98 is actuated by a suitable control (not shown) located adjacent the driver's seat in a well known manner.

At small openings of throttles 95, that is, when only small charges are passing through each branch, there is ordinarily a tendency for the fuel particles to settle out of the mixture due to the slow velocity at which it is 130

moving. To avoid such a tendency each branch is provided with automatic passage restricting valves which open according to the blast of the entering charge and thus always cause the fuel mixture to enter the engine ports 16 at high velocity. Each branch has an inner tube 100 of slightly smaller diameter than the inner diameter of the branch located therein adjacent the branch connection to the engine port 16. Preferably these tubes 100 are held in place by ears 101 cut out and bent up from the walls thereof, these ears 101 being clamped between the manifold and cylinder block, as shown in Fig. 2. Each tube 100 has a transverse hinge pin 102 upon which two flapper valves 103 are pivoted. These valves 103 are urged to closed position by the spring 104 which is connected to valves 103 in the manner clearly illustrated. The crescent-shaped opening 105 between tube 100 and the inner walls of the branch provides an unrestricted fuel charge passage for idling.

A depression equalizing duct 106 interconnects all three branches at a point on the engine side of the manual throttles 95.

In normal operation, the engine maintains a depression in the air manifold 10 due to the spring closed main air valve 20. This depression acting through the ducts 94 draws primary air through the bushings 82 and liquid fuel up from the float bowl 60 through ducts 72 and 71 to canal 80 and thence through the three fuel jets 81 into the primary air stream forming an overrich mixture in each primary carburetor. This rich mixture is drawn through the holes 92 and delivered into the main air blast through the venturis 90 in each branch, thus forming a correct mixture for the engine. The vertical duct 71 is provided with a tapered gravity valve 110 which has an aperture 111 extending therethrough. At idling speeds sufficient fuel is ordinarily supplied through the hole 111 to supply the proper mixture. As the engine speed is increased the increased suction on the fuel jets 81 causes the valve 110 to be correspondingly lifted from its seat to permit a greater fuel flow to said jets. It is thus seen that valve 110 constitutes an automatic fuel metering valve for regulating the fuel flow to the primary carburetors.

Located above the gravity valve 110 is a disk check valve 112 which permits fuel to flow upward but which prevents any downward flow of fuel. It has been found that under certain conditions, for instance when the engine speed is suddenly reduced from high speed to low speed, the sudden reduction in the suction on the vertical column of fuel in ducts 71 and 72 permits this column to drop sufficiently to cause a temporary fuel starving of the engine. The function of check valve 112 is to prevent the fuel in ducts 71 and 72 from dropping under such condi-

tions and so enable the engine to idle properly immediately upon a sudden closing of the throttles 95.

It has been found that the three primary carburetor passages 76, 77, 78 are not always subjected to the same degree of suction, probably due to the different lengths and shapes of the rich mixture ducts leading from the primary carburetors to the venturis 90. In order to equalize the depression applied to all three primary carburetors and so obtain uniform rich mixtures therefrom a depression equalizing duct 115 is provided interconnecting the three passages 76, 77, 78 at a point adjacent the air and fuel jets. The distributor block 74 has three apertures 116 extending down into the three passages 76, 77, 78 in the same location relative to the air and fuel jets therein. The duct 115 in the separate block 117 is of such shape as to register with all three apertures 116. The block 117 is suitably secured to the top of block 74 by the two screws 118. (See Figs. 7 and 8.)

The operation of the device for accelerating the engine is as follows: Consider the engine idling with the throttles 95 in nearly closed position. Under this condition the air valve 20 will be open only a very small amount since there will be only a small depression in the air manifold 10. Now if the throttles 95 be suddenly opened the depression in manifold 10 will be suddenly increased. The dash pot piston 26 however will prevent air valve 20 from opening rapidly and hence this increased depression will act first on the primary carburetors 76, 77, 78 to provide a richer mixture for accelerating purposes. The damping effect of piston 26 decreases progressively as air valve 20 opens due to by-pass port 43 approaching being uncovered by the downward movement of piston 26. As soon as port 43 is uncovered the damping effect is greatly decreased whereupon valve 20 opens rapidly to supply sufficient air to the engine to give the desired increased power. It will be clear therefore that the distance port 43 lies below the upper edge of piston 26 when air valve 20 is closed determines the period of high damping of valve 20. This period may be varied by adjusting the vertical position of cylinder 25 as described above to give the best accelerating effect according to the temperature of the engine or any other operating conditions. If desired, the cylinder 25 may be arranged to be moved by a thermostatic device instead of manually as shown in the drawings and described in detail herein.

While the form of embodiment of the present invention as herein disclosed, constitutes a preferred form, it is to be understood that other forms might be adopted, all coming within the scope of the claims which follow.

What is claimed is as follows:

1. In a charge forming device for a multi-cylinder internal combustion engine having a

plurality of intake ports, an individual primary carburetor for supplying a fuel mixture to each intake port, each primary carburetor having a single fuel jet, a common duct 5 for leading liquid fuel to all of said jets, and a suction actuated fuel metering valve in said duct.

2. In a charge forming device for a multi-cylinder internal combustion engine having 10 a plurality of intake ports, an individual primary carburetor for supplying a fuel mixture to each intake port, each primary carburetor having a single fuel jet, a common duct for leading liquid fuel to all of said jets, 15 and a gravity valve in said duct for metering the fuel flow to all of said jets.

3. In a charge forming device for a multi-cylinder internal combustion engine having 20 a plurality of intake ports, an individual primary carburetor for supplying a fuel mixture to each intake port, each primary carburetor having a single fuel jet, a common duct for leading liquid fuel to all of said jets, and a two stage suction operated valve in said 25 liquid fuel duct for regulating the flow of fuel to said jets.

4. In a charge forming device for a multi-cylinder internal combustion engine having a plurality of intake ports, an individual 30 primary carburetor for supplying a fuel mixture to each intake port, each primary carburetor having a single fuel jet, a common duct for leading liquid fuel to all of said jets, and a suction actuated fuel regulating 35 valve in said duct, and a one-way valve in said duct permitting fuel to flow only toward said jets.

5. In a charge forming device for a multi-cylinder internal combustion engine having 40 a plurality of intake ports, an individual primary carburetor for supplying a fuel mixture to each intake port comprising a mixture passage having fuel and air inlets, and a depression equalizing duct interconnecting 45 the mixture passages of said primary carburetors for equalizing the engine suction thereon.

6. In a charge forming device for a multi-cylinder internal combustion engine having 50 a plurality of intake ports, an individual primary carburetor for supplying a fuel mixture to each intake port comprising a mixture passage having fuel and air inlets, said primary carburetors being positioned relatively close together, and a short depression 55 equalizing duct interconnecting said mixture passages.

7. In a charge forming device for a multi-cylinder internal combustion engine having 60 a plurality of intake ports, a main air manifold having a branch leading to each intake port, an individual primary carburetor for supplying an overrich fuel mixture to each of said branches comprising a mixture passage having fuel and air inlets, said primary

carburetors being located relatively close together and having individual outlet ducts leading to said branches, and a depression equalizing duct interconnecting said mixture passages.

8. In a charge forming device for a multi-cylinder internal combustion engine having a plurality of intake ports, an individual primary carburetor for supplying a fuel mixture to each intake port, said primary carburetors 70 each comprising a relatively small approximately horizontal mixture passage having an air inlet bushing therein, and a fuel jet entering said passage from the under side thereof and adjacent the inner end of said bushing, 75 said bushing having a projection on its inner end extending over but spaced from said fuel jet.

9. In a charge forming device for an internal combustion engine having a plurality of 80 intake ports, an air manifold having a branch for each intake port and a common main air inlet, an engine suction controlled air valve in said inlet, a dash pot for damping the opening of said air valve, said dash pot comprising 85 a piston connected to said air valve, a cylinder having a by-pass port opened and closed by said piston for decreasing the damping effect upon said air valve in its more open positions, and means for changing the 90 position of said cylinder to vary the time of opening of said by-pass port by said piston.

10. In a charge forming device for an internal combustion engine, a main air inlet, a 95 spring closed air valve in said inlet opened 100 by the engine suction, a dash pot for modifying the action of said air valve, said dash pot comprising a piston and cylinder, a by-pass duct in said cylinder for decreasing the damping effect upon said air valve in certain positions, and means for adjusting the position of 105 said cylinder for varying the effective action of said by-pass duct.

11. A charge forming device for an internal combustion engine having in combination 110 a mixture passage, a fuel jet for delivering fuel to said passage, an air inlet bushing for admitting air to said passage, said bushing having a projection on its inner end extending over but spaced from the fuel jet to prevent the incoming air contacting directly 115 with the fuel jet.

12. In a charge forming device for a multi-cylinder internal combustion engine having a plurality of intake ports, an individual 120 primary carburetor for supplying a fuel mixture to each intake port, said primary carburetors each comprising a mixture passage having an air inlet bushing therein, and a fuel jet entering said passage adjacent the inner end of said bushing, said bushing having a projection on its inner end extending over 125 but spaced from said fuel jet.

13. A charge forming device for an internal combustion engine having in combination 130

a mixing chamber, a fuel inlet therefor, a main air inlet, a suction operated spring controlled valve therein, means for retarding the opening of said valve on opening of the throttle to enrich the mixture for acceleration, means for rendering the retarding means ineffective after a predetermined movement of the air valve, and means for varying the opening movement of the air valve before said retarding means is rendered ineffective. ¹⁰

In testimony whereof I hereto affix my signature.

FRED E. ASELTINE.
